[57] **CLAIM**

The ornamental design for a disc holding tool, as shown and described.

DESCRIPTION

FIG. 1 is a perspective view of a disc holding tool, showing my new design;

FIG. 2 is a top plan view thereof;

FIG. 3 is a front elevational view thereof, the rear elevational view being symmetrical thereto;

FIG. 4 is a bottom plan view thereof;

FIG. 5 is a right side elevational view thereof;

FIG. 6 is a left side elevational view thereof; and,

FIG. 7 is a perspective view of the disc holding tool in use. The broken lines shown in the drawings are for environmental purposes and form no part of the claimed design.
